HAIR-BLOWING DEVICE

Anastasios J. Kamataris, Clinton, Mass.

Application June 24, 1952, Serial No. 295,324

2 Claims. (Cl. 219—39)

This invention relates to a new and improved hair-blowing device, and the principal object of the present invention resides in the provision of a device which is small enough to be easily handled in one hand by the operator, such as a barber, and to fit into the pocket of the barber so that he may hold the device handily in his pocket while working, the blower being such that it is easily held in and extracted from the pocket, and a switch flipper thereon to start the motor and blow cut hair from the neck and possibly also the face and clothes of the person in the barber chair.

Sanitary rules in barber shops and even statutory requirements in some states provide against the use of any kind of powder-puff, duster, brush, or any other means for this purpose where such means would be used on more than one customer. Towels and napkins may be used but only where each one is fresh for each customer and this proves both a financial burden and an operative burden upon the barber, so that it is impractical to remove the cut hair, etc., by this means. It is an object of the present invention to obviate the above difficulties and to provide a small but relatively powerful device which is reasonable in cost and which the barber may keep in his pocket, said device being one that can be used for blowing the hair, so that the device never has to touch the customer's person in any way.

Other objects and advantages of the invention will appear hereinafter.

Reference is to be had to the accompanying drawings, in which:

Fig. 1 is a cross sectional view of a device according to my invention; and

Fig. 2 is a similar view but showing the head end only of a modification.

I provide first a housing of preferably cylindrical form indicated by the numeral 10 and having a circumference of about four inches and a length of about six inches, so that the entire device will fit handily in the operator's pocket. This housing contains a motor 12 wired in the usual manner as at 14 and having a commutator brush such as are used in small motors of this type, indicated at 16. The motor may be journalled at one end in a wall 18 and at the other end in a wall 20. There may be a cooling fan indicated at 22. One end of the housing may be closed as by a cap 24 having holes in it for the intake of the cooling air and holes may be provided near the opposite end of the housing at 26 for the egress of the motor cooling air.

So far as above described, the device is well known and forms no part of the present invention except to provide a handle and power means as will be more apparent hereinafter.

2

The housing 10 extends forwardly in cylindrical form as at 28, being open and forming a cup-shaped member in the center of which the motor shaft 30 extends. At its free end, this shaft is provided with a fan 32 so designed as 5 to take advantage of the full power output of the motor. Around the periphery of the cup-shaped member, there is provided a series of holes 34, the air being drawn into these holes into the cup-shaped member by the rotation of the fan, thus creating a draft thereon forwardly in the 10 direction of the arrow 36.

The open cup-shaped member may be closed by a nozzle generally indicated at 38, and having a rim 40 for securement to the open rim of the cup-shaped member. At the opposite end, the nozzle has a reduced nozzle tip 15 or the like 42 out through which a blast of air is forced by the fan as will be apparent.

A heater coil, generally indicated at 44, may also be applied, either in the nozzle 38 or in the cup-shaped member, and this coil will be appropriately wired to be 20 controlled by a thumb-switch 46. The wiring is such that the thumb-switch is movable in either of two directions and has a neutral, or current interrupting position. When the switch is pushed in one direction, it energizes both the motor and the coil, but when it is retracted to 25 its full extent in the opposite direction, it energizes only the motor, so either a warm or a cold blast of air is provided.

If it is desired to provide a greater blast of air, the 30 fan may be enlarged as shown in Fig. 2, by using a nozzle enlarged in diameter and a fan correspondingly increased in diameter.

Having thus described my invention and the advantages thereof, I do not wish to be limited to the details herein disclosed, otherwise than as set forth in the claims, 35 but what I claim is:

1. A barber's device for blowing and removing loose hair comprising a cylindrical housing adapted to be hand-manipulated and kept in the barber's pocket when not in use, an electrical motor in the housing, a cord for the motor, an open cup-shaped member at one end of the housing and connected thereto, a reduced nozzle on the member, a fan in the member driven by the motor and blowing air through the nozzle when the motor is energized, the nozzle being capable of being applied directly to the neck of the barber's customer by one-handed manipulation on the part of the barber to blow hair from the customer's neck without the use of brushes or towels and leaving the barber's other hand free to comb, etc., and the motor and fan being sufficiently powerful to provide a high speed blast of air to blow away the loose and cut hair.
2. The barber's hair blowing device of claim 1 including a heating element to heat the hair to dry the scalp of the customer.
